METAL RAILWAY TIE AND FASTENER

Application filed February 8, 1930. Serial No. 427,004.

This invention relates to the type of railway cross-tie and fasteners for securing track rails thereto that are adapted to be manufactured mainly of strong and light weight metal, such as wrought or rolled iron or steel, the invention having reference more particularly to a channel type of tie and to means for clamping rails to the tie.

An object of the invention is to provide an improved metal tie that shall be of such construction as to be adapted to be manufactured inexpensively and yet be strong and possess the desired degree of elasticity.

Another object is to provide an improved cross-tie that shall be of such construction as to be adapted to be expeditiously placed in position upon a road bed, or readily removed therefrom and from beneath the track rails when such may be required.

A further object is to provide improved means whereby to clamp a rail to a cross-tie of the above-described character without the necessity of using securing devices of such nature as might cause delays because of misplaced small parts or the breakage of delicate parts.

A still further object is to provide a strong and efficient cross-tie of such construction as to be adapted to be manufactured at small cost and which shall be durable and economical in use.

With the above-mentioned and other objects in view, the invention consists in a cross-tie of improved structure and in clamping means of novel structure for securing a conventional rail to the tie and assisting in directly supporting the rail in co-operation with the cross-tie, the invention consisting also further in the parts and combinations and arrangements of parts as hereinafter particularly described and further defined in the appended claims.

Referring to the accompanying drawings, Figure 1 is a top plan of a cross-tie and rail fastener constructed substantially in accord-

ance with the invention, fragments of two track rails being connected therewith; Fig. 2 is a fragmentary side view of the cross-tie and the rail in cross-section thereon; Fig. 3 is an end view of the cross-tie and side view 50 of a portion of a rail fastened thereto, on an enlarged scale; Fig. 4 is a fragmentary longitudinal section of the cross-tie and rail fastener connected therewith and also to a rail shown in cross-section; Fig. 5 is a transverse 55 section of the cross-tie and a rail positioned thereon; Fig. 6 is a perspective view of the improved rail clamp; Fig. 7 is a perspective view of a wedge block preferably comprised in the clamping means; and Fig. 8 is a transverse 60 section of the cross-tie and rail fastening means slightly modified whereby the rail thereon is secured in place by simple yet effective means.

Similar reference characters in the different 65 figures of the drawings indicate corresponding elements or features of construction herein referred to in detail.

As preferably constructed the cross-tie and fasteners are adapted to rigidly secure T- 70 rails thereon so that the track gauge cannot change in use, the rails illustrated having heads 1 and 1', respectively, each having a base 2 and a web 3, the fasteners being designed to be associated with such form of 75 rail.

More specifically each cross-tie has a bottom plate 4 and two opposite side walls 5 and 6 spaced apart and integral with the bottom plate. At the middle portion of the cross-tie the side wall plates are pressed inwardly and the bottom plate forced upwardly to constitute a rib 9 and relatively close side wall portions 8 and 9, adapted to prevent longitudinal shifting of the cross-tie in the ballast 80 of a road bed, the middle portion of the cross-tie thus being slightly elastic so as to have but slight tendency to fracture while retaining the necessary tensile strength. Preferably 85 the bottom plate adjacent to the middle por-

tion has spurs 10 composed of metal of the bottom plate punched out and downward from apertures 11, 11'. The upper portion of each side wall has a rail seat 12 which is 5 lower than the adjacent portions of the wall so that the rail seated thereon cannot shift laterally; the seats practically constitute a track gauge and prevent spreading of the rails. The wall 5 has outward extending ribs 10 13 and 14 at opposite ends of each one of the rail seats, the opposite wall 6 having similar ribs 13' and 14'.

Each rail fastener comprises two rail base seats 15 and 16 that are turned over at one 15 edge to constitute acute-angled top or clamp plates 17 and 18 respectively which are adapted to engage the top portions of the rail base, and the clamp plates have extension plates 19 and 20 fixed thereto, each having fingers 21 and 22 on opposite ends thereof that project over the adjacent ribs and have crooks 23 and 24 respectively that engage the under sides of the ribs to prevent a rail from being accidentally torn loose from a tie. Preferably a series of teeth 25 are provided in 25 each clamp jaw formed by the plates 15 and 17, and to afford ample strength back of the teeth a reinforcing pad 26 is welded to the parts 15 and 17 and also to the extension plate 19. The base plates 15 and 16 have supporting legs 27 and 28 respectively that extend down to the tie bottom plate 4 for support. The legs have a suitable number of bolt holes 29 therein receiving bolts 30 and 35 30' by which the clamp jaws are forced to grip a rail base by forcing the legs each towards the other, the legs preferably having foot plates 31 and 32 respectively that afford broad support on the bottom plate 4 of the tie. Preferably each side wall 5 and 6 has two holes 33 slightly higher than the tie bottom and arranged so as to be below the base of the rail and on opposite sides of the clamp legs, each being adapted to receive a wedge. 40 45 Two bolts 34 and 34' are arranged in the holes so as to extend through the side walls, each bolt having a wedge shaped head 35 arranged in one of the walls and a wedge 36 in the opposite wall, each bolt having a nut 37 thereon, each wedge having a hole 38 therein to receive the bolt. The head 35 and the wedge 36 bear upon the foot plate of a leg whereby to tightly secure the foot plate to the tie bottom 4. 50 55 When so desired the foot plates may be rigidly secured to the tie bottom, each by means of bolts 39 and 39' having each a nut 40 bearing upon the top of the foot plate, the bolt head being arranged under the tie bottom plate 4, in lieu of the above-described wedge devices.

In practical use the ties are laid on a roadbed in a conventional manner and firmly support the track rails, the rails being secured 60 to the ties as above explained. The teeth 25

are forced to bite into the edges of the rail base and prevent creeping of the rail on the tie, particularly on hills, the gripping clamps ordinarily preventing the creeping without the teeth when the roadway is level. One or both parts of the rail clamps may be conveniently removed from place and the tie removed from a rail when repairs must be made.

What is claimed is:

1. A railway rail fastener having a pair of base plates provided each with an acute-angled top plate and a tooth to grip a rail base, each top plate being provided with opposite fingers to engage the upper portion of a tie, and means to force the base plates each towards the other. 75

2. A railway rail fastener having a pair of base plates provided each with an acute-angled top plate to grip a rail base, each top plate being provided with opposite fingers having each a crook to engage the upper portion of a tie, and means to force the base plates each towards the other. 80

3. A railway tie and fastener having side walls provided at their tops with a plurality of outward-extending ribs, and a plurality of pairs of gripping clamps, each clamp comprising a base plate and an inclined top plate having fingers on opposite ends thereof provided each with a crook to engage one of the ribs, and means for forcing the clamps of the pair each towards the other and to a rail base. 90

4. A railway tie and fastener having a bottom plate and opposite side walls provided each with two rail seats having opposite ends and provided also with an outward-extending rib at each end of each end seat, and two pairs of clamping jaws having each a rail base seat plate and an acute-angled grip plate provided with crooks to engage the ribs, each rail base seat plate being provided with a leg having a foot secured to the bottom plate of the tie, the legs of each pair of jaws being detachably secured together. 100

5. A railway tie and fastener having a bottom plate and opposite side walls, the walls having rail seats on their upper portions, two pairs of clamping jaws having each a rail base seat plate and an acute-angled grip plate, each seat plate being provided with a leg plate to bear against the inner sides of the tie side walls, the leg plate having also a foot plate supported upon the tie bottom plate, bolts to co-operate with the leg plates to force the clamping jaws of a pair to a rail base, and means to secure the foot plates each to the tie bottom plate. 115

6. A railway tie and fastener having a bottom plate and opposite side walls, the walls having rail seats on their upper portions and wedge receptacles in their lower portions, two pairs of clamping jaws for gripping and supporting rail bases, each jaw be- 120 125 130

ing provided with a leg plate to engage the side walls, each leg plate having a foot plate bearing upon the tie bottom plate, wedge blocks to operate in the wedge receptacles respectively and upon an adjacent foot plate, and bolts to co-operate with the leg plates to force the clamping jaws of a pair to a rail base.

5 In testimony whereof, we affix our signatures on the 1st day of February, 1930.
